UNITED STATES PATENT OFFICE.

DANIEL MAGNY, OF ISSOUDUN, FRANCE.

INSTALLATION FOR THE WASHING AND COMBING OF PIGS' BRISTLES.

Application filed April 6, 1921. Serial No. 459,142.

(GRANTED UNDER THE PROVISIONS OF THE ACT OF MARCH 3, 1921, 41 STAT. L., 1313.)

To all whom it may concern:

Be it known that I, DANIEL MAGNY, citizen of the Republic of France, residing at Issoudun, Indre, in the Republic of France, have invented new and useful Improvements in Installations for the Washing and Combing of Pigs' Bristles (for which I have filed applications in France, July 16, 1917, granted October 15, 1918, under No. 489-10 586, and Germany, July 5, 1920, granted March 18, 1922, under No. 353,550), of which the following is a specification.

This invention relates to an apparatus or installation for the washing and combing 15 of moistened or scalded pig's bristles.

The accompanying drawings set forth by way of example various embodiments of this invention, wherein:

Fig. 1 is a side elevation of the whole 20 installation.

Fig. 2 is a front view of a wheel or drum used for disentangling and washing the bristles.

Fig. 3 is a plan view of a machine for 25 washing and for assembling the bristles in parallel disposition.

Fig. 4 is a side elevation of a combing machine which likewise forms part of the installation.

Fig. 5 is a detail view showing the operation of the wheel represented in Fig. 2.

Figs. 6 and 7 are views respectively in plan and in section on the line 7—7 of conveyor chains for the machines shown in

Fig. 1, in the portion wherein they are in contact.

Fig. 8 is a sectional view showing the combs of the combing machine.

Fig. 9 is a detail view of one of the combing units, on the same plane as Fig. 1.

To commence the operation, the raw bristles are introduced between the radial members of the wheel in the direction of the axis, and by reason of the rotation of the said wheel in the direction of the arrow

marked *a* (Fig. 1) and of the internal teeth

A thereof, the bristles are washed and disentangled within a tank *z* filled with water, passing thence by their own weight between the bars *B* whereby they may be taken up from the bottom of the said tank during the rotation of the wheel 2 by the external forked members *C* in small piles and automatically dropped into the receptacle

3 by means of the stop-piece *D* which trips up a rocking member *D'* secured to the shaft *D''* carrying the forked members *C* (Fig. 5). The said receptacle is provided with a double bottom *E*, and the impurities adhering to the bristles are detached therefrom during the operation by reason of their weight and pass through the said double-bottom. A rotating mill *F* with radial arms is caused to rotate continually in the water and thereby draws along the bristles and keeps them in movement, the latter being picked up during their passage by the forked members *G* provided with saw-teeth whose form is shown in Fig. 4 and which deposit them in the inclined troughs *H*, the shaft supporting the said forked members being given to this effect a reciprocating motion in the arc of a circle. The bristles thus spread upon the said inclined troughs are then pushed by the rake *I* under the pressing member *J* (Fig. 4) and are thereby collected in a bunch according to what is termed "wet combing."

The said pressing member *J* as well as the shaft carrying the forked members *G* receive their reciprocating motion by means of two chains *L'* (Figs. 1 and 4) secured to the cranks spaced 180° apart upon a disc actuated by the shaft *K*. This latter shaft is provided with the cams *L* acting upon the rollers *M* secured to each of the branches *N'* pivoted to the frame *N*, the said frame being raised at each movement by the springs *O* (Fig. 1). By reason of this motion, the pressing member *J* is alternately raised and lowered. Two springs *P* (Figs. 1 and 4) secured to the upper portions of the said frame are used to absorb the shocks produced by the sudden lifting of the frame. The bristles are then taken out by hand by a workman who deposits the same upon the sprocket chains *Q*, which latter are used to feed the bristles into the combing machine 4.

Upon their entire passage through the combing machine the bristles maintained at the middle part thereof by the sprocket chain *Q''* and the sprocket chains *Q'*, which pass over the toothed wheels *W* and *W'*, are combed on each side of the said chains while passing through the machine by the combs *R* which rotate in a direction perpendicular to the path of the chains in

such manner as to comb the bristles on each side of the chains both above and below, the shafts thereof being actuated by the gear wheels S (see Figs. 1, 4, 6 and 7).
 5 The bristles then descend in the combed state upon two slides T T' disposed below and in the prolongation of the chains Q''. Above each of the comb shafts R¹ there is disposed a shaft Y supporting clearing combs U keyed on said shafts Y. Each of the shafts Y is actuated by means of a rod V secured on a plate at the end of the shaft in such manner that the latter is imparted an angular reciprocating movement. By
 10 15 these means the teeth of the combs R and U are adapted to intermesh, whereby the combs R are cleaned from the bristles which may remain attached thereto. The operation is completed in this manner. After
 20 25 this stage, the raw bristles may be straightened at once or may be placed in the sulphur apparatus if white bristles are required.

The hereinbefore described installation is particularly applicable to the preparation of scalded pig's bristles.

With the present machine, two workmen can effect a daily production of two hundred kilogrammes of washed and combed bristles, 30 that is to say two men are enabled to produce as high an output with this machine as fifteen men occupied with carrying out like production by hand. By giving greater dimensions to the various parts of the apparatus a still greater yield could be obtained. Furthermore, no waste material is produced.

Having now described my invention, what I claim as new and desire to secure by Letters Patent is:

40 1. An installation for the washing and combing of moistened or scalded pig's bristles comprising in combination a tank, a washing drum therein provided with teeth and bars into which the raw bristles are introduced, a washing receptacle, washing liquid in said receptacle, a mill with radial arms rotating in said receptacle inclined troughs for straightening the bristles delivered by said mill, means for pressing said
 45 50 bristles, means for combing said bristles and means for actuating said drum, mill and pressing means.

2. An installation for the washing and combing of moistened or scalded pig's

bristles comprising in combination a tank, a 55 washing drum therein provided with teeth and bars into which the raw bristles are introduced, a washing receptacle, washing liquid in said receptacle, a mill with radial arms rotating in said receptacle, inclined troughs for straightening the bristles delivered by said mill, a pressing member having a reciprocating motion, means for combing said bristles and means for actuating said drum, mill and pressing member.

3. An installation for the washing and combing of moistened or scalded pig's bristles comprising in combination a tank, a 60 washing drum therein provided with teeth and bars into which the raw bristles are introduced, a washing receptacle, washing liquid in said receptacle, a mill with radial arms rotating in said receptacle, inclined troughs for straightening the bristles delivered by said mill, means for pressing 65 said bristles, endless chains receiving the bristles from said troughs, cooperating endless chains receiving the bristles delivered by the aforesaid chains and holding said bristles tight together, rotating 70 combs for combing the ends of said bristles extending out of said chains and means for actuating said drum, mill, pressing member, chains and combs.

4. An installation for the washing and combing of moistened or scalded pig's bristles comprising in combination a tank, a washing drum therein provided with teeth and bars into which the raw bristles are introduced, a washing receptacle, washing liquid in said receptacle, a mill with radial arms rotating in said receptacle, inclined troughs for straightening the bristles delivered by said mill, means for pressing said bristles, endless chains receiving the bristles from said troughs, cooperating endless chains receiving the bristles delivered by the aforesaid chains and holding said bristles tight together, rotating combs for combing the ends of said bristles extending out of said chains, cleaning combs having a reciprocating motion, and means for actuating said drum, mill, pressing member, chains and combs.

In testimony whereof I have signed my 105 name to this specification.

DANIEL MAGNY.
